Patented Feb. 1, 1927.

UNITED STATES PATENT OFFICE.

JOHN L. BROWN, OF LONG BEACH, CALIFORNIA.

VACUUM TUBE.

Application filed May 5, 1922. Serial No. 558,631.

This invention relates to electrical apparatus and more particularly to vacuum tubes for various uses, and more especially to a type of vacuum tube for wireless signal apparatus.

Vacuum tubes of the type including plates, filaments and grids are hermetically sealed and so constructed that it is practically impossible to make renewals, replacements, adjustments and variations as to the enclosed plates, grids and filaments, and especially without breaking or severing the tube glass to provide access to the enclosures. This makes it impractical to attempt to renew, replace, adjust or vary the enclosed elements in the tube.

An object of the present invention is to provide a novel vacuum tube consisting of a tube member or bulb combined with a mercury column, these elements being so connected that by fall of the mercury in the column, a vacuum, or partial vacuum, will be established in the vacuum chamber, and means are provided for closing the chamber mechanically above the mercury column so as to effectually maintain the vacuum in the vacuum member hereinafter called the vacuum tube.

An object is to provide a vacuum apparatus in which there is combined a vacuum tube and a mercury column, having a cell open to atmospheric pressure and into which the mercury column may recede from its standpipe when the same is hermetically but removably attached to a contiguous portion of the vacuum tube. An object is to provide means for closing communication between the vacuum tube and the mercury standpipe after the vacuum has been created, and especially an object is to provide means manually adjustable after the establishment of the vacuum, substantially without inversion or other manipulation of the mercury column.

Another object is to provide an improved filament device in the vacuum tube, and, further, an object is to provide an improved plate and grid device. Also an object is to provide for the effective removal, adjustment, alteration and replacement of the elements within the vacuum tube without destroying or injuring the same and without requiring the breaking of the tube wall and repairing the same, or resealing the same by fusion thereof.

An embodiment of the invention is de-

scribed in the following specification and illustrated in the accompanying drawings, in which—

Fig. 1 is a diagrammatic sectional view of a device embodying the invention.

Fig. 2 is a diagrammatic view showing a form of the multiple filament.

Fig. 3 is a plan view of an improved form of plate.

Fig. 4 is a side elevation of an improved form of grid.

The apparatus is shown as embodied, in one of its forms, in a vacuum tube which may include a bulb like body 2 provided with means for holding suitable grid, filament and plate devices common in wireless and other electrical apparatus. Such means I prefer to construct in the form of an annulus which here is secured to a flange like portion 2' of the vacuum tube. In the carrier ring 3 there is mounted a removable bushing or core 4 normally sealed upon the carrying ring 3 to maintain a vacuum but providing for the removal of the core 4 for permitting replacement, renewal, adjustment, inspection and for other purposes, as of the plate, filament and grid devices, which latter are, preferably, carried or mounted upon the inner face of the core 4, upon the outer face of which are provided the terminals or binding posts for the several plate, grid, and filament devices respectively indicated as a plate P, a grid G and a filament F. This, therefore, enables the insertion of these elements by the mounting of the core 4 upon the fastening ring or carrier 3 and upon injury or destruction of the enclosed elements, the core may be removed and changes and inspection made as desired and then this is returned in place without injury of the apparatus.

Suitable means are provided for the establishment of a vacuum in the vacuum tube 2 and means are provided for maintaining the vacuum, which enables the removal of the vacuum tube from the vacuum producing means without destroying the vacuum in the tube. For this purpose the vacuum tube is provided at any suitable portion thereof with a valve seat 5 as in a neck portion 2^a of the tube and the tube neck is adapted to be connected to any suitable means for establishing a vacuum. Such means may consist of a simple standpipe 6 open at its upper end, which is adapted to be registered with, and detachably connected to, the neck 2^a as by

a coupling 7 capable of maintaining a pressure tight joint. The lower end of the standpipe 6 is uncovered in a well 8 of suitable size so that when a column of mercury is sustained up in the standpipe 6, and when the vacuum tube has been attached thereto, after the column of mercury M has been released, its fall under action of gravity will produce a vacuum, or partial vacuum, in the vacuum tube 2 in the well known manner of a mercury barometer. After the vacuum has been established, in whatever manner this may be secured, in the tube 2, the latter is adapted to be closed as by the seating of a valve 9 upon the valve seat 5 of the tube 2. When the vacuum producing means is of the type here shown, including the mercury column, the valve may be closed by a device including a part which is exposed to be manually engaged. Such part may consist of a handle 10 on the upper end of a spindle 11 suitably supported in well 8 and having a pinion 12 engaging a gear 13 which is secured on the lower end of a vertical shaft 14 supported in the standpipe 6. The upper end of the shaft 14 is provided with a coupling or socket member 15 and this is designed to be detachably coupled to the complementary end of a threaded shank 16 of the valve 9, which shank turns in a nut 17 fastened in the tube neck 2^a. Turning the handle member 10, therefore, rotates the shaft 14 and this by engagement with the screw shank 16 causes the valve 9 to be pressed to its seat and effectually seal the vacuum tube 2. Thereafter this tube, for any purpose, may be removed from the vacuum producing standpipe 6 without destroying the vacuum in the tube.

A further feature of my invention consists in providing means for increasing the length of life of a vacuum tube and for obviating frequent renewal of the filaments and, further, for providing a variable capacity and to that end I provide what might be termed a multiple filament, such, for instance, as is illustrated in Fig. 2 in which a number of filament strands 20 each have one end connected to a common terminal 21, while each has an individual terminal 22 leading, for instance, to the exterior of the mounting 4 as above described.

From this it will be seen that any one of the filament strands 20 may be thrown separately into circuit or any combination of the same may be utilized, thus providing for variable capacity. By providing separate strands of filaments, one may be utilized until it becomes inoperative or destroyed and then the circuit can be thrown onto the other usable filaments as occasion may require, in this manner increasing the serviceability of the vacuum tube before necessitating dismantling and renewal.

Another object is to provide plates, grids

and filaments of increased effective area within a given length of grid or filament and given size of plate and to that end I have shown in Fig. 3 a plate structure in which a single strand 23 is coiled into a helix and this is arranged in a series of stretches disposed in parallel position in a common plane, in this manner securing a large area of strand 23 within limited dimensions.

A filament and a grid of increased effective area may likewise be constructed by utilizing a strand as 24, Fig. 4, coiled in helical form and the helix thus formed may also be again coiled into helical form. It will be seen that by this construction, where space is limited, a large area of a single strand can be produced.

When the electrical grid, filament, or plate conductors are made of helices, they may be wound upon a strand core as a bundle of wires 24^a, or this core may be in the form of a helix 24^b, or the combination as shown in Fig. 4.

In the erection of the vacuum producing means the vacuum tube is filled with the mercury, while in an upright position, and the lower end of the standpipe 6 may be temporarily sealed as by a cap or sleeve 13^a which may be formed on one side of the gear 13. By screwing the standpipe 6 down into the cap or sleeve 13^a, the apertures formed in the sides of the cap can be closed by the lower end of the sleeve, and in this way the level of mercury in the standpipe can be maintained therein at a higher point than that which is in the well. When it is desired to form the vacuum in the tube, on reversely screwing the standpipe 6 the apertures in the sides of the cap can be uncovered and the mercury then, which is in the standpipe, will tend to fall and approach the level of the mercury in the well. This sleeve may be internally threaded with a left hand thread to engage complementary threads on the adjacent end of the standpipe 6 and by this means the latter is closed while in the upright position of the filled tube 2. The tube is then inverted with the standpipe adjusted to the position shown in Fig. 1 and the cap 13^a is then turned off or back to permit escape of the mercury into the well. At this time the valve 9 would be open. The valve may remain open so long as the tube is connected to the standpipe 6, or may be closed as desired.

The valve is closed when the vacuum tube is removed from the standpipe to maintain the vacuum in the tube.

It will be seen that it is not necessary to remove and invert the mercury standpipe since it may be charged by uncovering the upper end of the tube 2 by removing the filament base; in which case the gear cap 13^a will be in closing position.

Various modifications and changes may

be resorted to within the spirit of the invention as claimed.

What is claimed is:

1. A vacuum producing means including a well, a standpipe mounted to extend down into the well, a cap at the lower end of the standpipe and having a port to open and close by rotating the cap relative to the standpipe, a stem mounted in the standpipe and extending through the cap, a gear upon the cap, a second gear in mesh with the first gear, a spindle extending upwardly from the second gear, a handle upon the upper end of the spindle, a coupling at the upper end of the standpipe adapted to receive a vacuum tube, and a socket upon the upper end of the stem adapted to engage and operate a valve of a vacuum tube.

2. A device of the class described comprising an open ended container, a carrier ring mounted upon one end of the container, a closure threaded into the carrier ring carrying a plate, filament and grid which are disposed within the container, means providing a valve seat in the other end of the container, and a valve mounted upon the container adapted to seat thereon.

3. A device of the class described comprising a container adapted to have a vacuum produced therein, said container having two openings formed therein, a carrier ring secured to the container about one of the openings, a closure threaded into the carrier ring, a filament, grid and plate carried by said closure and disposed within the container, means providing a valve seat in the other opening, an apertured nut mounted in the last named opening adjacent the valve seat, a screw threaded into said nut,

and a valve closure carried by said screw 40 adapted to seat upon said seat.

4. A device of the class described comprising a container having open ends, one of which is larger than the other, a carrier ring mounted upon the large end of the container, a closure detachably mounted upon the carrier ring carrying an electrode disposed within the container, means providing a valve seat in the small end of the container, an apertured nut mounted in the 50 small end of the container, a screw threaded into the nut, and a closure carried by the screw adapted to seat upon said valve seat.

5. A device for exhausting vacuum tubes comprising a container adapted to hold a liquid, a tube having its lower end disposed within the container and its upper end extending above the top of the container, a shaft rotatably mounted within said tube, means upon the upper end of the shaft to 55 operate a valve upon rotation of said shaft, and means for rotating said shaft.

6. A device for exhausting vacuum tubes comprising a container adapted to hold a liquid, a tube having its lower end disposed within the container and its upper end extending above the top of the container, a shaft rotatably mounted within said tube, means upon the upper end of the shaft to 60 operate a valve upon rotation of said shaft, 70 a handle rotatably mounted in the container, and gears connecting the handle to said shaft whereby the shaft may be rotated by the handle.

In testimony whereof I have signed my 75 name to this specification.

JOHN L. BROWN.
